UNITED STATES PATENT OFFICE.

LEONARD S. DOTEN, OF CHICAGO, ILLINOIS.

FLUID-PRESSURE PUMP.

Application filed October 24, 1922. Serial No. 596,603.

(FILED UNDER THE ACT OF MARCH 3, 1883, 22 STAT. L., 625.)

To all whom it may concern:

Be it known that I, LEONARD S. DOTEN, a citizen of the United States, stationed at Chicago, Ill., have invented an Improvement in Fluid-Pressure Pumps, of which the following is a specification.

The invention described herein may be used by the Government, or any of its officers or employees in prosecution of work for the Government, or by any other person in the United States, without payment of any royalty thereon.

This invention relates to an improved air lift, and has for its object to provide means whereby air under pressure is admitted into the lower end of the eduction column, is there mixed with the water and rises at the proper velocity into a head tank and is from there piped by gravity to the point desired.

The objects in view are to provide a simple, durable and inexpensive structure of a character that will, after being installed, need little or no further attention, there being no wearing parts and therefore little deterioration.

A further object being to so proportion the eduction column as to provide the maximum lift of liquid at the minimum expense of fluid pressure.

A further object being to provide diminished pressure at the discharge outlet of air supply line, and an effective method of mixing the air with the water without increasing the frictional losses.

These and other objects will appear in the following description, and be finally pointed out in the appended claims.

While a preferred form of the device is shown and described, it will be understood that slight changes in the form and minor details of construction may be resorted to without departing from the spirit of the invention.

Similar numerals indicate corresponding parts in all the figures of the drawings in which:

Fig. 1 is a side elevation, partly in section, of the improved air lift.

Fig. 2 is a cross section on line 2—2 of Fig. 1.

Fig. 3 is an enlarged vertical section

through the parts at the lower end of the eduction pipe.

Fig. 4 is a detail view of the double conical fluid velocity controlling member. 55

Fig. 5 is a cross section on line 5—5 of Fig. 3.

Fig. 6 is a cross section on line 6—6 of Fig. 3. 60

Fig. 7 is a cross section on line 7—7 of Fig. 3.

Fig. 8 is a detail section of the nozzle.

Fig. 9 is a cross section on line 9—9 of Fig. 8. 65

Fig. 10 is a detail section showing a modified form of foot piece of cylindrical formation.

Referring to the drawings, it will be seen that the air lift consists of a pipe for conveying a mixture of air and water from a point a considerable depth below the surface of the water in the well to a point above the surface of the ground. This pipe is generally known as the "eduction pipe" 75 and it can be of one diameter throughout its length or of a gradually increasing diameter from the point of inlet to point of discharge. The other parts of the air lift consist of an air pipe line for the air supply, a foot-piece, and a tail-piece extending below the point where the fluid under pressure is admitted to the eduction pipe. 80

The air lift is especially adapted for use in very deep wells of small diameter and in lifting corrosive liquids such as acid or salt water. It is a pump of large capacity for wells of small diameter. The air lift pump makes little or no use of the kinetic energy of the air as it flows into the inlet device. 90 The air is introduced at a certain distance below the surface of the water, dependent upon the required lift of water above the free surface of the water in the well. The air flows into the column of water and the bubbles of air are diffused throughout the column of water in the eduction pipe. This condition results in lessening the specific gravity of the contents of the eduction pipe and as a result of this, the solid column of 100 water on the outside of the pipe forces the lighter column within the pipe to a higher level. The air being constantly supplied to the lighter column within the eduction pipe

causes the flow to be continuous. As the air particles rise toward the outlet of the eduction pipe, they gradually expand in size due to diminished pressure. This results in an increased velocity of flow.

There are two important factors to be taken into consideration in designing an efficient air lift. The velocity of the air-water column must be sufficient to avoid, as far as possible, what is termed "slippage," that is, the discharge of the air bubbles through the water without imparting an upward motion to the water surrounding them. The second is the loss of energy due to friction which results from high velocities of flow in the upper portion of the eduction pipe. In designing an air lift, it is therefore necessary to use pipes of different diameters in making up the eduction pipe in order to control the velocities of flow within certain limits.

While experiments have proved that the air lift will operate very satisfactorily if a foot piece of cylindrical formation, as shown in Fig. 10, is used, it was found that by combining the essential features of the cylindrical form with a Venturi tube, as illustrated in the preferred form, it is possible to introduce the air into the eduction pipe at a diminished pressure.

The high velocity of water at the throat of the Venturi tube coming in contact with the entering jet or air moving nearly parallel to the flow of water and both jets impinging upon the surface of an inverted cone causes a rapid and thorough mixing of the air and the water particles. The more completely this action takes place, the higher the efficiency of the apparatus.

The annular space at the outlet of the air nozzle is of much dimensions that it cannot be obstructed either with particles of sand or other foreign substances or by corrosion, but admits of a free flow of air with little loss in pressure head.

Referring to the drawings it will be seen that casing 1 of the well is of the ordinary construction, into which eduction column 2 extends down below the normal water head shown at line 3-3. The eduction column is preferably made up of a series of sections increasing in size toward the top and extending into a head tank 4, mounted upon supports 5 above the level of the ground. The eduction column 2 beneath the water level is provided with the foot piece 6. Below the foot piece is a continuation of the eduction column, extending beneath the foot piece a considerable distance, and is known as the tail piece 7, terminating at its extreme end in a bell 8.

An air pressure pipe extends from a source not shown down into the well parallel to the eduction pipe, and communicates with the foot piece through passage 10. The

upper end of the eduction pipe is provided with a deflector plate 11, and the head tank 4 is provided with a gravity outlet pipe 12. The foot piece 6 may be of cylindrical form, as shown in Fig. 10, but is preferably reduced or tapered in opposite directions, as shown in Fig. 3, thus providing the throat 13 at a point adjacent to the discharge opening 14 of the nozzle 15 mounted at its lower end at 16 in the inner end 75 of the air inlet passage 10. From the throat 13 the inner diameter of the foot piece increases and is mounted at its upper end at 16 in the eduction column coupling 17. The lower end of the adjoining section of 80 the eduction column being mounted in the opposite end of said coupling.

Set screws 18 are threaded through the coupling member 17 and enter lugs 19 formed integral with, or secured to the 25 double conical shaped member 20, the outer diameter of the lower portion of the double conical member increasing upwardly at approximately the same rate as the foot piece 6 increases above the throat. From immediately above the lugs 19, the conical member 20 extends into the eduction column and is tapered to a point.

The double conical member or spreader is preferably tapered to a point at its lower 95 end, and rests with its extreme end within the upper end of the nozzle 15, and is firmly located therein by the spider 21, the upper end of the nozzle 15 being beveled off on its inner surface to provide free passage of the 100 air.

It will be noted that the Venturi shaped foot piece is tapered from the base of the nozzle 15 to its upper end, and from there gradually increases up to the lugs, and from 105 there the conical member tapers to its extreme upper end. The lugs 19 are preferably tapered in both directions to offer the least resistance to the passage of the fluid on its way toward the distributing tank, 110 being noted that no abrupt change in area of the space occupied by the mixture on its passage from the nozzle to the head tank is found.

By tapering or reducing the capacity of 115 the tail piece from its lower end to the throat at the upper end of the nozzle provides for the mixing of the air and water in the most effective manner. From the point at which the mixture is made, the 120 capacity of the passage is gradually increased, thereby reducing the pressure and permitting the gradual expansion of the air particles, thus causing an increase in velocity 125 of the mixture. The eduction pipe is gradually increased in size throughout its entire length up to the head tank, where said eduction column discharges against the deflector plate and into said tank, from which 130 said discharge is piped by gravity. The

capacity of the throat of the foot piece, the area of the nozzle, and the gradual increase for the passage of the mixture, are arranged in such proportion as to bring about the 5 most efficient results.

Having thus described my invention, what I claim as new and desire to secure by Letters Patent is:

1. A fluid pressure pump, comprising an 10 eduction column, a foot piece arranged beneath the normal level of the liquid to be raised and having a portion of rapidly diminishing area and a portion of gradually increasing area, and means for admitting 15 fluid under pressure centrally into the foot piece at the point of least water pressure and highest water velocity.

2. A fluid pressure pump, comprising an 20 eduction column, a foot piece arranged beneath the normal level of the liquid to be raised, means for reducing the interior area of the foot piece, and means for admitting fluid pressure centrally into the foot piece at the point of its least area.

25 3. A fluid pressure pump, comprising an eduction column, a foot piece arranged beneath the normal level of the liquid to be raised, a fluid velocity controlling member mounted in the foot piece, and means for 30 admitting fluid pressure centrally into the foot piece at the point of least water pressure and highest water velocity.

4. A fluid pressure pump, comprising an 35 eduction column, a foot piece arranged beneath the normal level of the liquid to be raised having an inverted conical portion, a conical shaped member mounted in said conical portion, said parts cooperating to 40 gradually increase the internal area of the foot piece, and means for admitting fluid under pressure into the foot piece.

5. A fluid pressure pump, comprising an 45 eduction column, a foot piece arranged beneath the normal level of the liquid to be raised having an inverted conical portion, a double conical shaped member adapted at its lower end, in conjunction with said conical portion, to increase the interior area of the foot piece relatively slowly, and at its 50 upper end relatively rapidly, and means for admitting fluid under pressure into the foot piece.

6. A fluid pressure pump, comprising an 55 eduction column, a foot piece of Venturi formation, and means for admitting fluid pressure centrally into the interior of the foot piece at the point of its least area.

7. A fluid pressure pump, comprising an 60 eduction column, a foot piece of Venturi internal formation, a tail piece, and means for admitting fluid pressure centrally into the foot piece at the point of least water pressure and highest water velocity.

8. A fluid pressure pump, comprising a 65 tapered eduction column, a tapered foot

piece, a tapered tail piece, and means for admitting fluid pressure into the foot piece at the point of greatest velocity of the liquid to be lifted.

9. A fluid pressure pump, comprising a 70 tapered eduction column, a tapered foot piece, a tail piece, and means for admitting fluid pressure into the foot piece at its most reduced portion.

10. A fluid pressure pump, comprising an 75 eduction column extending from below the normal level of the liquid to be raised to the point of discharge and provided with a Venturi shaped portion, means for admitting fluid under pressure into the eduction pipe 80 at the point of its least area, and means for gradually controlling the velocity of the contents of the eduction column.

11. A fluid pressure pump, comprising an 85 eduction column extending from below the normal level of the liquid to be raised, to the point of discharge, means for admitting fluid pressure centrally into the eduction pipe at the point of its least area, and means throughout its length for controlling the 90 velocity of the contents of the eduction column.

12. A fluid lift, comprising a tapered eduction column extending from beneath the normal level of the liquid to be raised, to the point of discharge, having a tail piece 95 rapidly decreasing in area and then gradually increasing in area, a foot piece, and means for admitting fluid pressure into said tail piece centrally at the point of least area.

13. A fluid lift, comprising an eduction 100 column extending from beneath the normal level of the liquid to be raised, to the point of discharge, having a tail piece, a foot piece rapidly decreasing in area through part of its length, and gradually increasing in area 105 through part of its length, and means for admitting fluid pressure into the foot piece centrally, at the point of its least area.

14. A fluid lift, comprising an eduction 110 column extending from beneath the normal level of the liquid to be raised, to the point of discharge, having a tail piece, a foot piece regularly and rapidly diminishing in area through part of its length and gradually increasing in area through part of its length, 115 and means for admitting fluid pressure at the point of least area.

15. A fluid lift, comprising an eduction 120 column extending from beneath the normal level of the liquid to be raised, to the point of discharge, a tail piece, a foot piece rapidly decreasing in area through part of its length and gradually increasing in area through part of its length, and a nozzle centrally located within the foot piece for discharging fluid pressure toward the gradually increasing portion.

16. A fluid lift, comprising a tapering eduction column extending from beneath the normal level of the liquid to be raised, to 130

- the point of discharge, a tail piece, a foot piece rapidly decreasing in area through part of its length, and gradually increasing in area through part of its length, and a nozzle in communication with a fluid pressure supply having a cylindrical body portion and a tapered discharge centrally located at the upper end of the decreasing portion of the foot piece.
17. A fluid lift, comprising an eduction column extending from beneath the normal level of the liquid to be raised, to the point of discharge, a tail piece, a foot piece rapidly decreasing in area through part of its length and gradually increasing in area through part of its length, and a nozzle in communication with a fluid pressure supply having its discharge end increasing in area at a rate approximating that of the increase in area of the foot piece.
18. A fluid lift, comprising an eduction column extending from beneath the normal level of the liquid to be raised, to the point of discharge, a tail piece, a foot piece, rapidly decreasing in area through part of its length and gradually increasing in area through part of its length, a nozzle in communication with a fluid pressure supply having its discharge end located at the point of least area in the foot piece, and increasing in area at a rate approximating that of the increase in area of the foot piece.
19. A fluid lift, comprising an eduction column, a foot piece, a fluid pressure inlet, a tapered fluid pressure velocity controlling member mounted above the inlet with its lower end entering said inlet, and means for concentrating the flow of liquid at the point of discharge of the nozzle.
20. A fluid lift, comprising an eduction column, a foot piece, a fluid pressure inlet having a nozzle, a fluid velocity controlling member tapered at its ends and extending into the fluid pressure nozzle.
21. A fluid lift, comprising an eduction column extending from beneath the normal level of the liquid to be raised to the point of discharge, means for admitting fluid pressure centrally, means for increasing the velocity of the liquid up to the point of discharge of the fluid, then gradually decreasing the velocity of the mixture above the fluid pressure discharge.
22. A fluid lift, comprising an eduction column extending from beneath the normal level of the liquid to be raised, to the point of discharge, means for admitting fluid under pressure at the lower end of the column, and means for first increasing, then gradually decreasing, and then rapidly decreasing, and finally gradually decreasing the velocity of the flow through the eduction pipe.
23. A fluid pressure pump, comprising an eduction column, a foot piece, means for admitting fluid pressure centrally into the foot piece, and means for gradually diminishing the velocity from the point of discharge of the fluid supply.
24. A fluid pressure pump comprising an eduction column, a foot-piece, means for admitting fluid pressure centrally into the foot-piece, and means for increasing the area of the foot-piece from said point of admission to point of discharge of the eduction column.

LEONARD S. DOTEN.
